(57) **CLAIM**

We claim the ornamental design for a vacuum cleaner attachment, as shown and described.

DESCRIPTION

FIG. 1 is a top perspective view of a vacuum cleaner attachment showing our new design; FIG. 2 is a front view thereof; FIG. 3 is a rear view thereof; FIG. 4 is a left side view thereof; FIG. 5 is a right side view thereof; FIG. 6 is a top view thereof; and, FIG. 7 is a bottom view thereof.

The broken lines are included for the purpose of illustrating the unclaimed portions of the article and form no part of the claim.
